UNITED STATES PATENT OFFICE.

GEORGE HILLARD BENJAMIN, OF NEW YORK, N. Y.

METHOD OF PURIFYING RAW WOOL

1,238,873.

Specification of Letters Patent.

Patented Sept. 4, 1917.

No Drawing.

Application filed May 4, 1916. Serial No. 95,350.

To all whom it may concern:

Be it known that I, GEORGE HILLARD BENJAMIN, a citizen of the United States, residing at New York, in the county and State of New York, have invented certain new and useful Improvements in Methods of Purifying Raw Wool, of which the following is a specification.

My invention relates to a process of treating raw wool for the purpose of obtaining clean wool, wool grease and suint.

The object of my invention is to treat raw wool to obtain the products above specified without using water in the treating operations. The use of water in the cleaning operation is a disadvantage, for the following reasons:

(A) Lanuginic acid, a constituent of wool, is soluble in warm water. It is desirable that such acid should not be removed from the wool, as it is of value in effecting reactions with mordants and dye stuffs.

(B) Suint, consisting largely of potash salts and organic acids, is soluble in water. It is desirable to obtain this body in a dried form. Where water is used the water must be evaporated, thereby involving the cost of evaporating apparatus, fuel, etc.

(C) In washing operations, where water is employed, alkalis are likewise used, which tend to saponify the oils and also act destructively upon the fiber of the wool, making it harsh and dry.

(D) Where water is employed, the water is often disassociated, the oxygen derived therefrom uniting with the greases to produce fatty acids which act destructively upon the fiber of the wool, and also decrease the percentage of commercially available greases which may be obtained.

There are still other reasons why the use of water is objectionable, but those above stated are the main reasons prohibiting its use.

It has heretofore been suggested to extract the fatty matters from wool by the action of warm hydrocarbon fluids, such as naphtha, gasoline, etc. This step has been found objectionable, owing, among other reasons, to the very serious fire risk involved. My improved process contemplates:

First: Softening the grease by the employment of a light and heated oil.

Second: Removal of the grease and oil by the solvent action of a volatile non-combustible compound consisting of a hydro-

carbon and chlorinated carbon, such for instance as a mixture of benzol and a carbon tetra-chlorid.

Third: Removal of dust scales, suint, etc., by the action of warm moving air currents of varying humidity.

To carry my invention into effect, I place a certain quantity of wool in a receptacle, and then force through it, a light oil having approximately a temperature of 150° F. I prefer to use a vegetable oil, such for instance as cotton seed oil, as I find it has a greater solvent effect upon wool grease than other vegetable oils. I may, however, use a mineral oil, such for instance as a very light Russian paraffin oil, but the effect of this oil is not as good, owing to the paraffin which it carries. I prefer that the oil shall be bleached.

After the wool is thoroughly saturated with the oil (which occurs in anywhere from thirty minutes to an hour), the oil and such of the wool fat as has been softened or dissolved by it, is drawn off as far as may be. This may be accomplished by allowing the wool to stand, exerting pressure upon the wool, or by the action of a centrifugal machine; after which the wool is immersed in a mixture of a fluid hydrocarbon and a fluid chlorinated carbon, preferably benzol (C_6H_6) and carbon tetra-chlorid (CCl_4) in approximately the following proportions: Benzol 90% and carbon tetra-chlorid 10%.

Other fluid hydrocarbons and other combinations of carbon with a halogen, may be employed. I prefer, however, to use those described, as I find that the benzol has greater solvent properties than any of the fluid hydrocarbons, and the carbon tetra-chlorid has

greater solvent properties, is more fluid than other combinations of carbon with a halogen, and possesses the property of rendering the mixture non-combustible. The respective amounts of the two substances, i. e., the hydrocarbon and chlorinated carbon, may be varied in accordance with the character of the wool.

The cleaner the wool, the smaller the percentage of carbon tetra-chlorid required. The effect of the mixture is to dissolve the wool greases. The time required to dissolve the greases will vary from fifteen minutes to an hour, depending upon the physical characteristics of the wool mass,

i. e., whether it is open or connected, whether it is full of grease and dirt, or fairly clean.

After the greases are finally dissolved, the

remaining portion of the solution, *i. e.*, the hydrocarbon fluid with the dissolved grease, is drawn off, the carbon tetrachlorid having at this time substantially evaporated. A 5 fresh mixture containing a smaller percentage of carbon tetrachlorid is then introduced to wash out, as far as possible, the remaining greases. This last mixture is then drawn off and the wool heated in any suitable receptacle, to a sufficient temperature 10 (approximately 150° F.) to volatilize any remaining part of the mixture, but not sufficiently high to injuriously affect the wool.

The treated wool is then withdrawn from 15 the receptacle and introduced into a suitable drying apparatus, for instance, such as described in U. S. Letters Patent No. 1,172,575, granted to William A. Wood on Feb. 22, 1916, and therein subjected to the action of 20 dehydrated air currents introduced under pressure, and having a temperature of approximately 90° F. The action of the flowing warm air currents is first to dry the dust scales, sweat bulbs and other foreign substances, and then to pick up these bodies and 25 carry them out of the apparatus. The time required to remove these bodies will depend somewhat upon the condition of the wool, air pressure and whether or not the wool is 30 agitated while in the apparatus. Generally, from one to two hours is sufficient to remove these bodies. The condition of the wool can be determined by examining the air currents leaving the apparatus. When the air currents 35 show that they are not carrying any of the bodies mentioned, the cleaning is practically accomplished.

I prefer that the air currents shall have a 40 temperature of approximately 90° F. The temperature, however, may be increased up to 130° F. I prefer that the humidity of the introduced air should not exceed 25%, although it may be raised, with certain grades of wool, to 75%. I find it advisable to increase 45 the humidity when the sweat bulbs are not fully separated by the treatment heretofore described. The action of the water carried by the air is to soften the sweat bulbs and cause them to separate from 50 the wool fibers.

After the wool has been subjected to the treatment above described, warm dehydrated air, *i. e.*, at 95° F. is again introduced and transmitted through the wool until examination 55 of the wool shows that it is thoroughly clean.

The extracted greases can be treated along well known lines for obtaining pure greases,

and the powdered suint separated from the wool and collected from the outgoing air, can 60 likewise be treated for obtaining potash, nitrogenous and other bodies which it carries. The fluid hydrocarbon and the fluid chlorinated carbon as evaporated from the wool, may be condensed and purified in any suitable apparatus to be again used. 65

The first step described, that is, treating with a light oil, while of distinct advantage, not only acting as a solvent for the wool greases but serving to put the wool in a better 70 condition for the subsequent action of the hydrocarbon and carbon halogen mixture, may be omitted, in which case the wool after heating to approximately 90° F. is at once treated with the hydrocarbon and carbon 75 halogen mixture, the succeeding steps of the process being as above described.

Having thus described my invention, I claim:

1. The method of purifying raw wool, 80 which consists in first, removing the wool grease by the successive solvent action of a heated oil and of a mixture of benzol and carbon tetrachlorid, and second, the remaining matters by the action of transmitted air 85 currents.

2. The method of purifying raw wool, 80 which consists in first, removing the wool grease by the successive solvent action of a heated oil and of a mixture of benzol and 90 carbon tetrachlorid, and second, the remaining matters by the action of transmitted and heated air currents.

3. The method of purifying raw wool, 85 which consists in first, removing the wool grease by the successive solvent action of a heated oil and of a mixture of benzol and carbon tetrachlorid in the approximate proportions of 90% of the former and 10% of the latter, and second, the remaining matters 100 by the action of transmitted air currents.

4. The method of purifying raw wool, 105 which consists in first, removing the wool grease by the successive solvent action of a heated oil and of a mixture of benzol and carbon tetrachlorid, and second, the remaining matters by the action of transmitted air currents having a range of temperature between 90° and 130° F. and a moisture content of between 25% and 75%. 110

In testimony whereof, I affix my signature, in the presence of two witnesses.

GEORGE HILLARD BENJAMIN.
